US0D1048601S

(12) **United States Design Patent** (10) **Patent No.:** **US D1,048,601 S**
(45) **Date of Patent:** **** Oct. 22, 2024**

(54) **EGG INCUBATOR**

(71) Applicant: **SAILVAN TIMES CO., LTD.**,
Shenzhen (CN)

(72) Inventor: **Fudan Deng**, Shenzhen (CN)

(**) Term: **15 Years**

(21) Appl. No.: **35/518,645**

(22) Filed: **Jul. 26, 2023**

(80) **Hague Agreement Data**

Int. Filing Date: **Jul. 26, 2023**

Int. Reg. No.: **DM/231978**

Int. Reg. Date: **Jul. 26, 2023**

Int. Reg. Pub. Date: **Oct. 13, 2023**

(51) **LOC (14) Cl.** **30-99**

(52) **U.S. Cl.**

USPC **D30/199**; D30/108

(58) **Field of Classification Search**

USPC D30/108, 113, 115, 158, 159, 199;
119/300, 311, 322; D24/163

CPC A01K 41/00; A01K 61/17

See application file for complete search history.

Primary Examiner — Sheryl Lane
Assistant Examiner — Emily A Caven

(57) **CLAIM**

The ornamental design for an egg incubator as shown and described.

DESCRIPTION

1.1: Perspective

1.2: Right

1.3: Left

1.4: Front

1.5: Back

1.6: Top

1.7: Bottom

The broken lines illustrate portions of the egg incubator that form no part of the claimed design.

1 Claim, 7 Drawing Sheets
